UNITED STATES PATENT OFFICE.

WILLIAM G. KENDALL, OF NEWARK, NEW JERSEY.

VANITY-CASE.

1,299,733.

Specification of Letters Patent. Patented Apr. 8, 1919.

Application filed April 23, 1918. Serial No. 230,291.

To all whom it may concern:

Be it known that I, WILLIAM G. KENDALL, a citizen of the United States, residing at Newark, in the county of Essex and State of New Jersey, have invented certain new and useful Improvements in Vanity-Cases, of which the following is a specification.

This invention relates to vanity cases or similar containers for toilet articles such as 10 pressed powder and rouge tablets or the like, and the primary object of the present invention is to provide a novel and efficient means for retaining the articles within the case.

It is a further object of the invention to provide in a container of the class mentioned means for retaining the powder and rouge tablets in place, which means will be inconspicuous as a retaining means and will, at 20 the same time, enhance the artistic appearance of the article as a whole, the said retaining means having the appearance of an artistic form of partition wall dividing the interior of the body of the container into 25 separate compartments housing the rouge and powder tablets and the respective puffs.

A further object of the invention is to provide in a retainer of the class mentioned, means for retaining in place the articles disposed therein, which means will serve, as 30 stated above, as a partition wall to divide the body of the container and also as a means for relatively bracing the front and rear walls of the body so that while such 35 containers are ordinarily made from light sheet metal, the one embodying the invention will have its walls so reinforced that they will not be liable to be crushed in or otherwise distorted.

The invention has as a further object to 40 provide a retaining means for the purpose stated such as will securely hold the rouge and powder tablets or similar articles within the container and will yet permit of ready 45 removal of the bases or supports for the tablets after the tablets have been consumed and it is desired to place fresh tablets within the container. Thus, not only may a lady making use of the vanity box, readily replenishing the same whenever she so desires, 50 but also the filling of the boxes in the factory may be accomplished in an expeditious manner and with little likelihood of injury to the tablets.

As above stated, the retaining means embodying the present invention is designed secondarily to serve as a partition wall dividing the interior of the container into separate compartments in which the rouge and powder tablets or cakes may be respectively housed, and a further feature of the invention resides in so forming this retaining member that in serving the purpose of a partition wall, it will prevent the powder puffs which are disposed within the compartments, coming in contact with each other so that there is no likelihood of powder from the rouge puff being deposited on to the face powder puff.

So far as the fundamental principles of 70 the invention are concerned, the invention contemplates the provision between the articles to be retained, of a normally expanded means which is interposed between the articles and acts against the same to hold the 75 articles firmly against relatively fixed elements which, in the illustrated embodiment of the invention, are the opposite end walls of the body of the container, the said normally expanded means being capable of compression so as to permit the disengagement 80 and removal of either or both of the articles.

In the accompanying drawings:

Figure 1 is a perspective view of a vanity case embodying the present invention,

Fig. 2 is a top plan view thereof, the lid of the case being shown open,

Fig. 3 is a vertical transverse sectional view taken substantially on the line 3-3 of 90 Fig. 2,

Fig. 4 is a vertical longitudinal sectional view on the line 4-4 of Fig. 2, and

Fig. 5 is a perspective view of the retaining member.

In the illustrated embodiment of the invention the retaining device constitutes a part of the vanity case and serves to hold within the case compressed tablets or cakes of rouge or face powder. However, this is to be considered as only one example of the 95 many uses to which the retaining device may be put for it is not essential that the articles to be retained be in the nature of powder tablets, nor is the device limited to use in connection with but two of such articles, 100 for it might be employed in retaining a single article within the case, or one or several of the retaining devices might be em- 105

- ployed in retaining more than two of the articles in place. It is also to be understood that I am not to be limited to the use of the specific retaining means illustrated in 5 the drawings and to be hereinafter described, inasmuch as normally expanded retaining members of many other forms may be employed for accomplishing the desired results.
- 10 In the drawings there is illustrated a vanity case preferably formed of light sheet metal and including a body indicated in general by the numeral 1 and a lid indicated in general by the numeral 2. The lid 2 is hinged as at 3 to the rear wall of the body 1, which wall is indicated by the numeral 4, the said body further including a front wall 5, arcuate end walls 6, and a bottom 7. Of course, if desired, the case may 15 be of some shape other than shown in the drawings, although it is preferable that the same be of the shape illustrated. As is usual in articles of this class, the lid 2 is provided with a marginal depending flange 20 25 8 which is designed to fit down over the upper edges of the walls 4, 5 and 6 of the body and the said walls of the body have their upper marginal portions struck in slightly, as indicated by the numeral 9, thus 30 forming a narrow shoulder 10 within the body 1. Also, as is usual in such articles, the front wall 5 is struck out near its upper end to provide a protuberance 11 designed to snap into a similarly formed socket 12 in 35 the forward side of the depending flange 8 of the lid 2, for the purpose of holding the lid in closed position and, in the present instance, the protuberance 11 is located above the shoulder 10, for a purpose which will 40 be presently explained.
- As before stated, the articles to be held within the case constitute in the present instance, a rouge tablet indicated for example, by the numeral 13, and a face powder tablet 45 14, and these tablets are compressed and housed within shallow hollow bases 15 each of which is provided with an annular upstanding wall 16 surrounding the respective tablet 13 or 14 as the case may be. While a 50 powder tablet can best be maintained in whole condition by the use of a shallow hollow base such as above referred to, and it is preferable to employ such a base where the retaining means of the present invention is 55 to be made use of, nevertheless, the retaining means will act equally as well with such tablets when the same are merely secured upon flat disk-like bases. As before stated, the 60 end walls 6 of the body of the case are of arcuate form and their curvature corresponds to the marginal contour of the tablets to be held so that when the tablets 13 and 14 are disposed within the body of the case at the opposite ends thereof, the outwardly presented sides of the tablets will

more or less snugly fit against the inner faces of the end walls 6 of the said body, the body being of such length as to provide sufficient space between the adjacent or inner sides of the tablets to accommodate the retaining 70 member as will be presently explained.

The retaining member embodying the present invention is indicated in general by the reference numeral 17 and the same is preferably formed from a strip of resilient 75 sheet metal bent to substantially sigmoidal form, as clearly shown in Figs. 2 and 5 of the drawings. Being of the form mentioned, the retaining member includes an intermediate portion 18, bowed portions 19 located at the ends of the intermediate portion 18, and inwardly curved terminals 20 which lie at opposite sides of the said intermediate portion 18 and which, in the normal condition of the said retaining member, are spaced 80 from the said intermediate portion 18, due to the resiliency of the bowed portions 19. By reference to Figs. 1, 2 and 4 of the drawings, it will be observed that the retaining device just described is to be positioned 85 between the tablets 13 and 14 with its terminal portions 20 bearing against the adjacent sides of the powder tablets or their container members or bases 15, the resiliency of the bowed portions 19 serving to cause the terminal portions 20 to exert pressure against the tablets in the direction of the respective end walls 6 of the case, so as to securely hold the tablets in place. It will be apparent 90 that because of the inherent resiliency of the retaining member, it may be laterally compressed when removing the tablets or placing new tablets in position within the case. By reference to Fig. 3 of the drawings, it 95 will be observed that the height of the retaining member is such that when the member is properly assembled within the body of the case, the upper edge of one of its bowed portions 19 will rest beneath the shoulder 10 at the front of the said body of 100 the case and the upper edge of its other bowed portion 19 will engage beneath the hinge lugs forming a part of the hinge 3, the said retaining member being in this manner securely held within the body of the 105 case, although adapted to be removed upon slightly compressing the same and lifting out the tablets. In order to disengage the protuberance 11 from the socket 12 in the flange 8 of the lid 2 when it is desired to 110 swing the lid to open position, it is necessary to exert a slight inward pressure against the upper portion of the front wall of the box so as to slightly spring this portion of the said wall in an inward direction and while 115 the retaining member extends between the front and rear walls of the body and relatively braces these walls, nevertheless, the stated inward springing of the upper portion of the front wall is not prevented be- 120 125 130

cause of the fact that the retaining member is of such height as to stop short of the protuberance 11.

It will be evident, as before stated and particularly by reference to Figs. 1, 2 and 4 of the drawings, that the retaining member serves also as a partition dividing the interior of the case body into two compartments, each housing a respective one of the 10 pressed powder cakes or tablets and each also housing a powder puff designed for use in connection with the powder cake contained in that respective compartment, the said puffs being indicated in the drawings 15 by the numeral 21.

In certain of the claims which are to follow I will refer to a fixed element located within the container. As before stated, the device of the present invention is capable of 20 employment in securing in place a single one of the articles provided it is disposed between the said article and the relatively fixed element, and inasmuch as either of the articles illustrated in the drawings may be considered as a fixed element located within the 25 container, one of said articles might be replaced by a wall of the container.

Having thus described the invention, what is claimed as new is:

30 1. The combination with an article container and articles disposed therein, of a re-

taining member disposed between the articles and comprising a resilient body of sigmoidal form having terminal portions bearing, through the resiliency of the respective 35 body portions, against the said articles in a direction to bind the same against the respective end walls of the container.

2. The combination with an article container and articles disposed therein, the opposite walls of the container being provided 40 interiorly with projections, of a retaining member disposed between the said articles and comprising a resilient body of sigmoidal form having the upper edges of its bights 45 engaging beneath the projections upon the walls of the container and having its terminal portions bearing, through the resiliency of the respective body portions, against the said articles in a direction to bind the 50 same against the respective end walls of the container.

3. A device for the purpose stated comprising a resilient member of sigmoidal form 55 normally expanded with its terminal portions spaced from its intermediate portion whereby pressure exerted inwardly against the said terminal portions will be resisted by the resiliency of the said member.

In testimony whereof I affix my signature. 60

WILLIAM G. KENDALL.
